UNITED STATES PATENT OFFICE.

REUBEN D. TITTLE, OF SPRINGFIELD, OHIO.

WASHING MACHINE.

Application filed January 13, 1922. Serial No. 523,838.

To all whom it may concern:

Be it known that I, REUBEN D. TITTLE, a citizen of the United States, residing at Springfield, in the county of Clark and State 5 of Ohio, have invented certain new and useful Improvements in Washing Machines, of which the following is a specification, reference being had therein to the accompanying drawing.

10 This invention relates to clothes washing machines and is in the nature of an improvement on the application for patent filed by me March 2, 1921, Serial No. 449,251.

One object of the invention is to provide 15 a washing machine of this type which can be manufactured and assembled in large quantities and at a low cost.

In manufacturing and assembling the 20 pumps of a washing machine of this kind on a sheet metal tub, it is difficult to secure an exact alinement between the cylinders and the pistons and piston rods. To secure an exact alinement requires very close workmanship and is not practical when the machine 25 is being manufactured in quantity production. It is, therefore, a further object of the invention to produce a machine of this kind in which the pumps will operate in a satisfactory manner even though the 30 cylinders and piston rods are not in true alinement.

In a washing machine of this character 35 the cleansing action is secured largely by causing the hot soapy water, or suds, to pass through the clothes being washed, and to secure an efficient cleansing action a maximum of agitation of the water is desirable. It is, therefore, a further object of the invention 40 to produce a machine of this kind which will cause the water to be forced through the clothes in practically all parts of the tub and will agitate the whole body of water in the tub.

A further object of the invention is to provide 45 a simplified and highly efficient operating mechanism for the pumps.

Other objects of the invention will appear as the mechanism is described in detail.

In the accompanying drawings Fig. 1 is 50 a top plan view of a washing machine embodying my invention; Fig. 2 is a side elevation with the frame partly in section; Fig. 3 is a sectional view taken on the line 3—3 of Fig. 2; Fig. 4 is a vertical sectional view 55 taken centrally through one of the pumps

and the vertical wall of the tub; Fig. 5 is a plan view of the connection between the piston rod and the cross head; Fig. 6 is a side elevation of said connection; Fig. 7 is an elevation of the nozzle plate, or escutcheon; Fig. 8 is a section taken on the line 8—8 of Fig. 7; Fig. 9 is a section taken on the line 9—9 of Fig. 7; Fig. 10 is a section taken on the line 10—10 of Fig. 7; Fig. 11 is a section taken on the line 11—11 of Fig. 7; Fig. 12 is a section taken on the line 12—12 of Fig. 4; Fig. 13 is a sectional detail view of the driving mechanism; Fig. 14 is a section taken through the gear housing, showing the driving gear; Fig. 15 is a detail view of the clutch operating cam; and Fig. 16 is a sectional detail view of the piston.

In these drawings I have illustrated one embodiment of my invention and have shown the same mounted upon a frame which, in 75 the present instance, is formed of angle iron and comprises four upright members, or corner posts, 1 connected at top and bottom by transverse members 2 and 3. Mounted on the main frame between the 80 upper and lower transverse members 2 and 3 and forming a part of that frame is a supplemental frame consisting of a bar 4 extending diagonally of the main frame and secured at its ends to the upright corner 85 posts 1. Extending from the other corner posts respectively are two bars 5 rigidly secured at their ends to said posts and having their inner ends bent to project laterally therefrom, as shown at 6, and rigidly secured to the bar 4, the two bars 5 being arranged substantially in line one with the other. The casting 7 has angle plates 8 which are located in the angles between the bars 4 and 5, rigidly secured to said 90 bars, and serve to reinforce and embrace the same. Mounted within the main frame is a clothes receptacle, or tub, 9 which is here shown as cylindrical in form and which rests upon the supplemental frame formed 95 of the bars 4 and 5. The main frame is of a length somewhat greater than its width and the cylindrical tub fits snugly between the side members 2 thereof, but the end members are spaced some little distance from 100 the walls of the tub. Mounted on the vertical wall of the tub 9 and in the present instance arranged on the outside of that tub are a plurality of pumps, in the present 105 construction four, which are spaced sub- 110

stantially equal distances apart about the tub. These pumps are preferably of the cylinder and piston type and, as here shown, each pump comprises a base 10 having a 5 suction, or inlet, chamber mounted on the supplemental frame and secured to the vertical wall of the tub near the bottom thereof. Each suction chamber has an inlet opening 11 which communicates with the interior 10 of the tub near the bottom thereof through an opening 12 therein. Arranged within the tub adjacent to the suction chamber of each pump is a nozzle plate, or escutcheon, 13 which forms a clamping plate by means 15 of which the base 10 is secured to the tub and which has in its lower portion an opening 14 in line with the inlet opening 11 of the suction chamber. Preferably the inlet openings 11 and 14 are separated from the 20 clothes in the tub by a screen to prevent the clothes from being drawn into the same and, as here shown, the nozzle plates 13 are provided with lugs 15 upon which a horizontal screen 16 is supported. This screen 25 is preferably formed in two or more parts, as shown in Fig. 1, to facilitate the placing of the same in position and the removal of the same from the tub. Mounted in the upper portion of each suction chamber 30 is a suction valve, 17, here shown as an ordinary flap valve seated upon an inwardly extending flange 18 carried by the walls of the suction chamber. Above this suction valve the base is provided with a discharge 35 opening, or outlet, 19 communicating with the interior of the tub through an opening 20 therein, below the normal level of the water.

The base, or suction chamber is preferably formed separate from the cylinder itself and, as here shown, has at its upper end a flange 21 upon which the cylinder 22 rests, the cylinder being secured in position by a collar 23 and suitable packing 24 being interposed between the parts to provide a tight joint. The cylinder is preferably secured at its upper end to the wall of the tub and has mounted therein a reciprocating piston 25 carried by a piston rod 26 which extends above the upper end of the cylinder and is adapted to be connected with suitable operating devices, by means of which it is reciprocated in the cylinder and the water drawn into the pump through 55 the openings 11 and 14 and discharged through the openings 19 and 20. More or less water will work its way past the piston and to prevent this water from being splashed from the upper end of the cylinder 60 I prefer to close the upper ends of the cylinder by a cap 27 having a stuffing box 28 for the piston rod. The upper end of the cylinder is provided with a breathing port 29 which may, if desired, communicate with 65 the interior of the tub, thus causing the

water which passes through the same to be returned to the tub. This breathing port may be arranged either above or below the level of the water within the tub and is preferably provided with a screen 30 to 70 prevent the clothes from entering the same.

In order that the water may be discharged forcibly into the tub and against and through the clothes in substantially all parts of the tub, I have provided each discharge opening 19 with a nozzle having a plurality of discharge openings, and constituting in effect a plurality of nozzles, each of which discharges in a different direction. In the present instance, the upper portion of the 75 nozzle plate 13 is provided with a transverse conduit 31, the edges of which rest upon the wall of the tub and which is secured thereto by bolts 32. The intermediate portion of the conduit is provided with a longitudinal slot consisting of three portions, each portion constituting in effect a separate nozzle. The portion 33 of the slot is so constructed that the water passing through the same will be discharged at a 80 downward angle. The portion 34 of the slot and nozzle is so arranged as to discharge the water in a substantially horizontal plane and the portion 35 is so arranged as to discharge the water upwardly. At the ends 85 of the conduit, beyond the respective bolts 32 are other slots or nozzles 36 which discharge the water in a substantially horizontal plane and obliquely to the radius of the tub. In this manner the water is discharged in a thin stream, or streams, in five different directions and is thus caused to come in contact with clothes in various 90 parts of the tub and to impart a maximum of agitation to the water in the tub.

In view of the difficulties encountered in assembling the pump and piston rod in true alinement, I have provided a floating piston, the body of which can assume a position slightly oblique to the piston rod. This 105 piston may be of any suitable character but that here shown is similar to the piston shown and described in the application for patent filed by me August 25, 1921, Serial No. 495,264. It is not necessary to 110 here describe this piston in detail as its essential characteristic, so far as the present invention is concerned, is the ability of the packing member of the piston to maintain the proper contact with the walls of the 115 cylinder when the piston rod is not in true alinement therewith. To this end the packing member 25^a is in the form of an 120 expandible ring mounted in the body of the piston and is acted upon by an expanding member 25^b arranged within the same to press it into contact with the walls of the cylinder. The packing member is thus 125 loosely mounted in the body of the piston so that the latter may have movement rela- 130

tively thereto when the piston rod is moved out of alinement with the same. In order to utilize this characteristic of the piston to its fullest extent I have provided means 5 for adjustably connecting the piston rods with the actuating devices. In the present machine the pumps are operated in pairs and I have arranged on each side of the tub a cross head, or operating bar, 37, the 10 respective ends of which are connected with two of the piston rods. Preferably the rods are adjustably connected with the cross heads and to this end each rod has at its upper end a spherical knob, or ball, 39 15 which is seated in a spherical socket 40 to provide for the universal adjustment of the piston rod. The socket 40 is divided longitudinally into two parts which are connected with the cross head by means of 20 bolts 41 extending through the ears 42 on the respective parts of the socket and through transverse slots 43 in the cross head. The openings in the heads 42 through which the bolts extend are in the form of 25 longitudinal slots 44. It will be apparent, therefore, that the connection between each piston rod and the cross head is universally adjustable. By moving the piston to the top of the cylinder and then adjusting the 30 connection between the piston rod and the cross head so as to arrange the piston rod in substantially a vertical position, the piston is enabled to accommodate itself to any irregularities in the position of the cylinder and will not bind or stick therein. 35

Each cross head is carried by and actuated by an operating rod 45 which is mounted for vertical sliding movement in a bearing 46 carried by the main frame of the machine 40 and is in the present instance shown as mounted on an upright member, or channel iron, 47 secured to the transverse members 2 and 3 of the main frame. These operating rods are arranged on opposite sides of 45 the main frame and each is connected at its lower end, by means of a link 48, with one end of a rock arm, or walking beam, 49, which is pivotally connected between its ends with the bracket 7, as shown at 50. Rocking movement is imparted to the rock arm 49 by means of a link 51 connected at one end with the adjacent end of the rock arm and at the other end with a crank arm 52 carried by a bushing 53 rotatably 55 mounted in a bearing 54, which bearing is carried by one of the bottom frame members 3 and a transverse member 55. Journaled in the bushing 53 is an operating shaft 56 the opposite end of which is, in the 60 present instance, journaled in bearings 57 formed in the side walls of a gear casing 58. Arranged within the casing and rigidly secured to the shaft 56 is a gear 59 which meshes with a pinion 60 also journaled in the walls of the gear casing 58

and connected with the shaft 61 which is driven from a motor 62. The motor and the gear casing are supported by the transverse bar 55 and a second transverse bar 63. A suitable clutch connection is provided 70 between the bushing 53 of the crank arm 52 and the shaft 56 and as here shown one member of the clutch is formed on the inner end of a bushing, as shown at 64, and the other member of the clutch is slidably 75 mounted upon and splined to the shaft, as shown at 65. The slideable member of the clutch has connected therewith a grooved collar 66 to receive a shifting cam 67 which is carried by a shaft 68 journaled in suitable bearings on the main frame. This shaft has connected therewith a crank arm 69 which is connected by a rod, or pitman, 70 with a second crank arm 71 carried by a shaft 72 mounted near the upper end of 80 the main frame and having secured thereto a lever 73 by means of which it may be actuated to rock the shaft 68 and thus impart movement to the cam 67 which will shift the movable clutch member from one 85 position to another. It will be noted that the pinion 60 is of small diameter and has but a few teeth while the driving gear 59 is of a large diameter and has a relatively 90 large number of teeth, thus securing the necessary reduction of speed between the two shafts by the use of two gears only. If desired, the driving mechanism may be utilized for operating the clothes wringer, and to this end I have shown the shaft 56 95 100 as having its end projecting beyond the outer wall of the gear casing 58 and provided with a beveled gear 74 which may be connected through a suitable vertical shaft and other beveled gearing with the wringer 105 shaft.

The operation of the mechanism will be readily understood from the foregoing description of the several parts thereof and it will be apparent that when the pumps are 110 operated the water will be drawn downwardly through the clothes in the tub, through the screen 16 and thence through the suction chamber of the pump into the cylinder. Because of the narrow openings in the discharge nozzles 33 to 36 and the force 115 and speed with which the water is discharged, little, if any, water will be drawn into the cylinder upon the upward movement of the piston, the bulk of the water being taken in through the suction chamber and valve 17. Upon the downward stroke of the piston the valve 17 will be closed and the water forcibly discharged through the nozzles 33 to 36 and into the clothes, thus 120 forcing the water through the clothes with which it comes in contact and agitating the whole body of water in such a manner as to cause it to pass through and through the clothes in the tub. Inasmuch as the water is 125 130

forced through the clothes by movements of the piston, that is drawn downwardly through the clothes by the suction stroke of the piston and forcibly discharged through the clothes on the discharge stroke of the piston, a constant circulation and agitation of the water is maintained and a very thorough cleansing action is secured. The mechanism as a whole is very simple in its construction and because of the character of the mechanism it can be produced and assembled in a wholly satisfactory, operative condition without the necessity of making fine adjustments or of mounting the parts in exactly true positions with relation of one to the other. Consequently, it can be produced in large quantities at a low cost. Further, the character of the mechanism is such that there is little likelihood of any part of it becoming inoperative or being broken, thereby reducing the cost of maintenance to a minimum.

While I have shown and described one embodiment of my invention I wish it to be understood that I do not desire to be limited to the details thereof as various modifications may occur to a person skilled in the art.

Having now fully described my invention what I claim as new and desire to secure by Letters Patent, is:

1. In a washing machine, a clothes receptacle, a pump comprising a lower portion having a suction chamber provided with an inlet communicating with said receptacle near the bottom thereof and having an outlet communicating with said receptacle at a point spaced from the bottom thereof, a check valve interposed between said inlet and said outlet, a cylinder mounted on and in open communication with said lower portion, a plate mounted within the wall of said receptacle and rigidly secured to said lower portion of said pump, said plate having a portion arranged in line with said outlet and constituting a discharge nozzle, a piston mounted in said cylinder, a piston rod connected with said piston, and an actuating device connected with said piston rod.

2. In a washing machine, a clothes receptacle, a pump comprising a lower portion having a suction chamber provided with an inlet communicating with said receptacle near the bottom thereof and having an outlet communicating with said receptacle at a point spaced from the bottom thereof, a check valve interposed between said inlet and said outlet, a cylinder mounted on and in open communication with said lower portion, a plate mounted within the wall of said receptacle and rigidly secured to said lower portion of said pump, said plate having a conduit communicating with the outlet for said pump and provided with a plurality of openings constituting a nozzle and ar-

ranged to discharge water in different directions into said receptacle, a piston mounted in said cylinder, a piston rod for said piston, and an actuating device connected with said piston rod.

3. In a washing machine, a clothes receptacle, a pump comprising a lower portion having a suction chamber provided with an inlet communicating with said receptacle near the bottom thereof and having an outlet communicating with said receptacle at a point spaced from the bottom thereof, a check valve interposed between said inlet and said outlet, a cylinder mounted on and in open communication with said lower portion, a plate mounted within the wall of said receptacle and rigidly secured to said lower portion of said pump, said plate having a transverse conduit provided at its intermediate portion with a slot having portions arranged to discharge the water into said receptacle in different directions with relation to the horizontal, said conduit also having slots at the ends thereof to discharge the water in said receptacle obliquely to the radius thereof, a piston mounted in said cylinder, a piston rod connected with said piston, and an actuating device connected with said piston rod.

4. In a washing machine, a clothes receptacle, a pump comprising a lower portion having a suction chamber provided with an inlet communicating with said receptacle near the bottom thereof and having an outlet communicating with said receptacle at a point spaced from the bottom thereof, a check valve interposed between said inlet and said outlet, a cylinder mounted on and in open communication with said lower portion, a plate mounted within the wall of said receptacle and rigidly secured to said lower portion of said pump, said plate having an opening in line with said inlet and having a conduit communicating with said outlet, said conduit constituting a nozzle and having openings arranged to discharge the water in different directions into said receptacle, a piston mounted in said cylinder, a piston rod for said piston, and an actuating device connected with said piston rod.

5. In a washing machine, a clothes receptacle, a series of pumps mounted on and spaced about the walls of said receptacle, each pump comprising a lower portion having an inlet communicating with said receptacle near the bottom thereof, and an outlet communicating with said receptacle at a point spaced from the bottom thereof, a check valve interposed between said inlet and said outlet, a cylinder mounted on and in open communication with said lower portion, a piston in said cylinder, a piston rod, an actuating device connected with said piston rod, a plate arranged within said receptacle and rigidly secured to the lower por-

tion of said pump, said plate having an opening communicating with the inlet to said pump and having a conduit communicating with the outlet for said pump and provided with discharge openings arranged to discharge the water in different directions into said receptacle, each of said plates also having a lug arranged above said inlet opening, and a screen extending transversely to 10 said receptacle and resting upon the lugs of the several plates.

6. In a washing machine, a clothes receptacle, a plurality of pumps mounted on said receptacle and each comprising a cylinder 15 having valve controlled communication with said receptacle near the bottom thereof, and having an outlet communicating with said receptacle at a point spaced from the bottom thereof, a nozzle structure communicating 20 with said outlet to forcibly discharge the water into said receptacle, a piston mounted in each cylinder, a piston rod connected with said piston and extending above the top of the cylinder, two cross heads, each connected 25 with a plurality of piston rods, an actuating rod connected with each of said cross heads and mounted for vertical reciprocatory movement, a rock arm pivotally mounted between its ends beneath said receptacle and connected at its ends with the respective actuating rods, a crank arm operatively connected with said rock arm, a driving shaft, clutch mechanism for connecting said shaft with said rock arm, and means for imparting 30 reciprocatory movement to said shaft.

actuating rods, and means for imparting rocking movement to said rock arm.

7. In a washing machine, a clothes receptacle, a plurality of pumps mounted on said receptacle and each comprising a cylinder 35 having valve controlled communication with said receptacle near the bottom thereof, and having an outlet communicating with said receptacle at a point spaced from the bottom thereof, a nozzle structure communicating 40 with said outlet to forcibly discharge the water into said receptacle, a piston mounted in each cylinder, a piston rod connected with each piston and extending above the top of the cylinder, two cross heads, each connected 45 with a plurality of piston rods, an actuating rod connected with each of said cross heads and mounted for vertical reciprocatory movement, a rock arm pivotally mounted between its ends beneath said receptacle and connected at its ends with the respective actuating rods, a crank arm operatively connected 50 with said rock arm, a driving shaft, clutch mechanism for connecting said shaft with said rock arm, and means for imparting 55 reciprocatory movement to said shaft.

In testimony whereof, I affix my signature hereto.

REUBEN D. TITTLE.
